UNITED STATES PATENT OFFICE.

HERBERT A. WALLACE, OF PITTSBURGH, PENNSYLVANIA, ASSIGNOR TO THE UNION SWITCH & SIGNAL COMPANY, OF SWISSVALE, PENNSYLVANIA; A CORPORATION OF PENNSYLVANIA.

RAILWAY SIGNALING.

1,294,731.

Specification of Letters Patent. Patented Feb. 18, 1919.

Application filed January 12, 1916. Serial No. 71,604.

To all whom it may concern:

Be it known that I, HERBERT A. WALLACE, a citizen of the United States, residing at Pittsburgh, in the county of Allegheny and State of Pennsylvania, have invented certain new and useful Improvements in Railway Signaling, of which the following is a specification.

My invention relates to railway signaling, more particularly it relates to the control of railway signals governing traffic over a railway switch or other traffic controlling device.

One object of my invention is to provide means for the control of a switch operating lever by a switch or switches operated thereby, jointly with the control of one or more signals governing traffic over the corresponding switch or switches, by means of a relay or other electromagnetic translating device which is energized in one direction or the other according as the corresponding switch is in one extreme position or the other, and which is deenergized and short-circuited when the switch is in an intermediate position. The control of the switch operating lever is effected by means of one or more locking or indication devices controlled by the relay which also controls the signals, so that the signals and the indication devices depend for their proper operation upon coincidence of position of the switch operating lever and the switch or switches operated thereby.

I shall describe one form and arrangement of apparatus and circuits embodying my invention and then point out the novel features thereof in claims.

The accompanying drawing is a diagrammatic view showing a railway switch and controlling apparatus therefor, together with signals for controlling traffic over said switch, and one form and arrangement of apparatus and circuits embodying my invention for the control of said signals.

In the drawing reference character B designates a straight portion of railway track from which branches off another track E through a switch A or other traffic control device. When this switch is in what I shall term its "normal" position (shown in the drawing) it completes the straight track B so that traffic on track B may pass over the switch from west to east without being deflected from the straight route, which I shall

term route #1 hereafter. However, when the switch is thrown to the opposite position, i. e. "reversed," it connects the branch E with track B, so that traffic on track B passing eastwardly over the switch is diverted to branch E and vice versa, westbound traffic on branch E passes over switch A to track B. This route, which comprises track B and branch E, I shall term route #2.

In order to govern traffic approaching the switch from either direction so that only one train can pass to the switch at a time, I provide preferably four signals designated R¹, R², L¹ and L², of which signals R¹ and R² are shown mounted on the same pole. Signal R¹ governs the passage of traffic from west to east over route #1 through the interlocking limits, which comprise that portion of the tracks extending from signal R¹ to signal L¹, and signal L¹ governs the passage of traffic over the same route in the opposite direction. Signal R² governs the passage of eastbound traffic through the interlocking limits over route #2, and signal L² governs traffic over this same route in the opposite direction. These signals normally indicate stop and, as I shall explain hereinafter, are controlled in such manner that but one signal at a time may be caused to display a proceed indication or "cleared," so that but one train may enter the interlocking territory at a time. Although I have shown four signals for governing traffic through the interlocking territory, in practice, one or more of these signals is sometimes dispensed with, for instance, signals R¹ and R² are sometimes combined into one signal which, when cleared, indicates to the engineer of an eastbound train that he may proceed through the interlocking territory, but it does not indicate to him which one of the two routes has been set up for him. These and similar changes are well known and easily made by those versed in the art and it is understood that I do not wish to limit myself to the particular arrangement of signals and controlling circuits shown in the drawing.

For the operation and control of the switch I provide apparatus and circuits similar to those described in Letters Patent No. 1,101,039 issued to G. R. Scattergood and myself on June 23, 1914, although I do not wish to limit myself to these particular circuits and apparatus. On the drawing I have

shown these circuits in dash lines for the purpose of distinction, the signal circuits being shown in full lines.

The switch operating mechanism comprises a motor M and a suitable actuating mechanism F. As here shown this motor M comprises two solenoids 10 and 11 which control a reciprocating plunger 12, which latter is operatively connected with a plate 37. This plate is provided with a cam slot 38, which actuates a roller 39 operatively connected with the switch rails by means of a rod 40. It will be seen that reciprocation of the plunger 12 will cause reverse movements of the switch A. Operatively connected with the plate 37 is a pole-changer P for a purpose which I will hereinafter explain. Although I have herein shown this particular type of motor device M, and actuating mechanism F, it is understood that I do not limit myself to these particular types, but that any suitable motor and switch actuating mechanism may be employed.

The motor M is controlled by means of a circuit controlling lever C, which is usually one of a plurality of levers comprised in an interlocking machine. This lever C may be of any suitable type; as here shown it is of a usual and well known type comprising a shaft 13 which is adapted to oscillate and which operates a plurality of contact fingers one of which, designated 18, controls the circuits for the solenoids of motor M.

43 is a source of current which may be either direct or alternating, and which as here shown is a battery. In the arrangement of control circuits herein shown, one or the other of the solenoids 10 or 11 is connected with the source 43 according as contact finger 18 engages with contact 45 or 44. It is understood however that this arrangement of control of the motor device M by the lever C is merely illustrative and that I do not wish to limit myself to this particular arrangement. The movements of the shaft 13 are as usual controlled by indication apparatus which, as here shown, comprises two indication devices Kⁿ and K^r, one for each direction of movement. Each of these indication devices as here shown comprises a segment 27 fixed to the shaft 13 and provided with a dog 28 adapted to engage with a latch 29, which latches are controlled by electromagnets N and R respectively. Each of the electromagnets N and R is provided with a circuit which is controlled by an electromagnetic device D as hereinafter explained. The circuits for these indication magnets are also controlled by contacts 25 and 26 operated by the shaft 13. These contacts are not moved during the first portion of the movement of the shaft 13 up to the point at which it is stopped by the dog 28 of one or the other of the indication devices,

but during the remainder of the movement of the shaft, the contacts 25 and 26 are reversed in position. This operation of contacts 25 and 26 is as here shown obtained by mounting the contact fingers loosely on the shaft 13 and moving them by pins 31, 32, 33 and 34 carried by collars 35 and 36 fixed on the shaft 13. It is understood, however, that the means herein shown for operating the contacts 25 and 26 is merely illustrative, and that I do not limit myself to this particular means.

The electromagnetic device D is a three-position relay which may be controlled by either alternating or direct current as described in the Letters Patent hereinbefore referred to. When alternating current is used to control this relay, the relay is preferably of a type in which the direction of movement of the armature or rotor is obtained by the polarity relation between currents in two windings, and in which the contact fingers assume a middle position in case of no current or of insufficient current in either or both windings. As here shown this relay is of a polyphase type comprising two windings, a and f and a rotor r, but I do not wish to limit myself to this particular type of relay. Rotor r operates contact fingers 60, 61 and 62, which coöperate with fixed contacts 14, 15, 16 and 16^a. When the relay is energized so that the fingers are swung to the left (which I shall term the normal energization of the relay), contacts 60—14 and 62—16 are closed and when the relay is energized reversely so that the contact fingers are swung to the right, contacts 61—15 and 62—16^a are closed. When the relay is de-energized or insufficiently energized so that the contact fingers are in the middle position, all contacts are open.

19 designates a source of alternating current, here shown as being a generator, to which are connected conductors 20. The winding f of relay D is constantly energized from these conductors 20 through wires 21 and 22.

T designates a transformer whose primary 41 is connected with conductors 20 and whose secondary 42 is connected with contact points 48, 49 and 50 of pole changer P. The movable contact fingers 17 and 17^a of the pole changer P are connected with the winding a of relay D by wires 23 and 24. It will be seen therefore that while the pole changer P is in one extreme position or the other, that is, when the switch actuating mechanism F occupies one extreme position or the other, the winding a is energized from transformer T in one direction or the other relative to the energization of the winding f, so that the contact fingers of relay D then occupy one extreme position or the other. When, however, the mechanism F is intermediate its two extreme positions,

the contact fingers 17^a and 17 of pole changer P are disconnected from transformer T and engage contacts 46 and 47 which are electrically connected by wire 51, so that the 5 winding a is then disconnected from the transformer T and placed on the following short-circuit: from winding a through wire 23, contact finger 17, contact point 47, wire 51, contact point 46, contact finger 17^a, wire 10 24 to winding a. The rotor r of relay D then assumes its middle position, so that all the relay contacts are open. The short circuiting contacts 46 and 47 are added to shunt from the winding a current which might 15 leak into wires 23 and 24.

In the drawing, the parts of the apparatus are shown in the positions which they occupy when the switch A occupies its normal position. The pole changer P is therefore in one of its extreme positions so that 20 relay D is energized in such direction that contacts 60—14 and 62—16 are closed and contacts 61—15 and 62—16^a are open. When it is desired to move the switch A 25 from its normal position to its reverse position, the shaft 13 of control lever C is rotated from its normal position shown in the drawing in the direction indicated by the arrow until the dog 28 of indication device 30 K^R engages the latch 29. In this position the contact finger 18 has been disengaged from contact 44 and has engaged contact 45 so that solenoid 10 is energized through the 35 following circuit: from battery 43, through wire 52, contacts 18 and 45, wire 53, solenoid 10, wires 54, 56 and 55 to battery 43. This causes solenoid 10 to draw the plunger 12 thereby shifting the plate 37 so that the 40 roller 39 is moved by the cam slot 38 and the switch A is reversed. As soon as this movement begins and while the upper longitudinal portion of the slot 38 is moving past the roller 39, the pole changer P is operated so that its contact fingers 17 and 17^a 45 disengage from contact points 49 and 48 and engage with contact points 47 and 46 thereby placing the winding a of relay D on short circuit so that all the contacts of this relay are then opened. The fingers 17 and 50 17^a of the pole changer continue to engage the points 47 and 46 while the switch A is being moved by the inclined portion of the slot 38. When the movement of the switch A is complete and the lower longitudinal 55 portion of the slot 38 is moving past the roller 39 the contact fingers 17 and 17^a are moved to engage with contact points 50 and 49 thereby connecting winding a with the transformer T in the direction opposite to that shown in the drawing. Relay D is now 60 energized in the reverse direction so that contacts 61—15 and 62—16^a are closed. The reverse indication magnet R is then energized by the following circuit: from battery 43, through wires 55 and 56, contact

15—61, wire 57, contact finger 25, wire 58, magnet R, wires 59 and 52 to battery 43. Magnet R then raises its armature thereby raising the latch 29 out of the path of dog 28 of indication device K^R, so that the movement of shaft 13 can be continued until the lever arrives at its reverse position. During this last portion of the movement, contact 25 is opened, thereby opening the circuit for magnet R, and contact 26 is closed thereby closing at that point the circuit for magnet N. 70

The operation of the apparatus for the movement of the switch A from the reverse to the normal position would be similar to 80 that just explained, hence, it need not be explained here in detail.

From the above description of the apparatus for controlling the movement of the switch it is evident that under ordinary conditions lever C, relay D and switch A occupy corresponding positions; thus, when the switch is in the normal position, lever C and relay D are also in their normal positions and when the switch is reversed, lever 90 C and relay D are also reversed. I utilize lever C and relay D for the control of the signals governing traffic over the switch as I shall now explain.

Reference character C' designates a circuit 95 controlling lever similar to lever C, generally of the same interlocking machine, and for purpose of distinction I shall hereinafter refer to lever C' as the signal lever and to lever C as the switch lever. Signal lever C' occupies normally a middle position shown in the drawing, in which position contact fingers 75 and 76 operated by the lever are out of engagement with their respective contact points. When the lever is turned to the 100 right, i. e., in the direction of the arrow marked "r", contact fingers 75 and 76 are brought into engagement with contact points 77 and 78 respectively. On the other hand, when the lever is thrown to the left, as indicated by arrow "l", these contact fingers engage contact points 79 and 80 respectively. The signals are governed by circuits which are controlled by these contacts in conjunction with similar contacts on the switch lever 105 C and also by contacts 16 and 16^a of relay D. For example, signal R¹ is controlled by the following circuit: from battery 43, through wires 55 and 56, contact 62—16 of relay D, wire 81, contact 76—78 of the signal lever 120 C', wire 82, contact 83 of the switch lever C, wire 84, signal R¹ and wires 85 and 90 to battery 43. It follows that in order to clear signal R¹ the signal lever C' must be thrown to the right, relay D must be in the normal 125 position so that contact 16 is closed and switch lever C must also be in the normal position so that contact 83 is closed. Similarly, the circuit for signal L¹ is from battery 43, through wires 55 and 56, contact 130

62—16 of relay D, wire 81, contact 76—80 of the signal lever C', wire 86, contact 87 of the switch lever C, wire 88, signal L¹, wires 89 and 90 to battery 43. It follows, therefore, that in order to clear signal L¹, signal lever C' must be thrown to the left, relay D must be energized normally and switch lever C must be in the normal position.

The circuit for signal R² is completed only when switch lever C and relay D are reversed and signal lever C' is thrown to the right, so that the following circuit is established: from battery 43, through wires 55 and 56, contact 62—16^a of relay D, wire 91, contact 75—77 of signal lever C', wire 97, contact 98 of switch lever C, wire 94, signal R², wires 95, 85 and 90 to battery 43. On the other hand, signal L² is cleared only when switch lever C and relay D are reversed and signal lever C' is thrown to the left, so that the following circuit is closed: from battery 43, through wires 55 and 56, contact 62—16^a of relay D, wire 91, contact 75—79 of signal lever C', wire 92, contact 93 of switch lever C, wire 99, signal L², wires 89 and 90 to battery 43.

The operation of the signals is easily understood from the foregoing description of the circuits. Suppose that the switch is in the normal position so that route #1 is established. If the operator desires to permit an eastbound train on track B to pass through the interlocking territory via route #1, he clears signal R¹ by throwing signal lever C' to the right. This closes at contact 76—78 the circuit for signal R¹ traced hereinbefore, so that signal R¹ is caused to indicate "proceed". At this time the circuit for signal L¹ (which as pointed out hereinbefore governs traffic over route #1 in the opposite direction) is open at contact 80 of signal lever C', which makes it impossible to clear signal L¹ as long as signal R¹ is in the proceed indication so that no opposing clear indication can be given over the same route. The circuits for signals R² and L² are now open at contact 62—16^a of relay D and contacts 98 and 93 of switch lever C so that it is also impossible to give clear signals for route #2.

In order to reverse the switch, the operator must first return signal lever C' to its middle or normal position. This is necessitated by a mechanical locking arrangement which forms no part of my invention and is well understood by those versed in the art, so that I have not shown it on the drawing. When signal lever C' is returned to its normal position, contact finger 76 breaks the circuit for signal R¹ so that this signal is caused to assume the stop indication. Since the other signals are also in the stop position, no train may enter the limits of the interlocking territory. The operator now reverses lever C so that switch A is reversed

as hereinbefore explained and relay D is also reversed in position. Relay D now closes at contact 62—16^a the circuit for both signals R² and L² and switch lever C closes the circuits for these signals at contacts 98 and 93 respectively. The operator may now clear either signal R² or L² governing route #2. If he desires to allow a westbound train on branch E to pass through the interlocking limits, he clears signal L² by throwing signal lever C' to the left so that contact finger 75 engages contact point 79 and completes the circuit for signal L². At this time the circuit for opposing signal R² is open at contact 77 of signal lever C' so that no opposing train on the same route may enter the interlocking limits. Also the circuits of signals R¹ and L¹ governing route #1 are open at contact 16 of relay D and contacts 83 and 87 of switch lever C, so that no train on route #1 may enter the interlocking limits from either end.

It is apparent from the above description of the signal circuits that after a certain route through the interlocking limits has been established by the switch it is possible to clear only either one of those signals which govern that route and it is impossible to clear either of the signals which govern the other route. This selection is automatically accomplished by the position of the switch lever C and relay D and the operator has control of the signals only in so far as he may select the direction in which a train movement is to be made over the route that has been established. This co-action of the switch lever and relay D is of great advantage in the control of the signals in that it constitutes a double check on the proper relative positions of the switch lever and the switch before a signal for any route leading over the switch may be cleared. Although ordinarily, both the switch lever and the relay D occupy positions that correspond to the position of the switch, it is not the best practice to rely on only one of these means for the control of the signal circuits, because it may happen that either lever C or relay D does not correspond to the position of the switch. For instance, the operator may throw the switch lever C until the latch of the indication device prevents further movement of the lever. The switch should now respond and give an indication of the completion of its movement by energizing the indication magnet so that the stroke of the lever may be completed. If, due to some derangement, the switch does not move at all or moves through only part of its stroke, the operator may, under the impression that the indication apparatus is out of order, lift the armature of the indication magnet manually and then complete the stroke of the lever, so that the switch lever and the switch are in non-corresponding positions. This

condition may also be brought about by a manual operation of the switch actuating mechanism on the ground—leaving the switch lever unmoved, so that it does not correspond in position with the switch. But it is of greatest importance for the proper functioning of an interlocking machine that all switch levers always correspond in position with the switches controlled thereby; and if this condition of non-coincidence of the switch lever and the switch should happen at an installation using the signal control circuits of my invention, no clear signal could be given over any route leading over this switch because the corresponding signal circuits would be open at the contacts of the relay D or at the contacts of lever C.

The use of the relay for the control of the signal circuits is of great advantage because it permits of greater economy in the use of wire than is possible when the signal control circuits are led through the interlocking territory and are controlled by contacts directly operated by the switch movement, as is sometimes done. This is especially true of extensive and complicated interlockings comprising a great number of switches and crossovers, where control of the signal circuits by contacts on the switch movements necessitates a very complicated net of conductors between the various switches and signals. So great, indeed, is the length of wire required in such interlockings that in general only the signals for the high-speed routes are thus wired, leaving signals for the low-speed routes without this protection. The partial protection thus secured is insufficient in the case of intersecting high-speed and low-speed routes because a false clear signal for a low-speed route may permit the passage of a low-speed train into or across an occupied high-speed route. Even this partial protection may be nullified by grounds on the contacts operated by the switch movements. But in the use of my invention the relays controlled by the switches are generally housed in a compartment of the interlocking tower, so that, without danger from grounds, they can be wired easily and cheaply in such manner that each signal is governed by all the necessary switches.

Although I have herein shown and described only one form and arrangement of signaling circuits embodying my invention, it is understood that various changes and modifications may be made therein within the scope of the appended claims without departing from the spirit and scope of my invention.

Having thus described my invention, what I claim is:

1. In combination, a railway switch having a normal and a reverse position, a relay controlled by said switch and having a nor-

mal and a reverse contact the former or the latter of which is closed according as the switch is in normal or reverse position, a lever for controlling said switch and having a normal and a reverse position corresponding to the said positions of the switch, a normal and a reverse contact operated by said lever and the former or the latter of which is closed according as the lever is in normal or reverse position, two signals governing traffic over said switch, a circuit for one signal controlled by the normal relay contact and the normal lever contact in series, and a circuit for the other signal controlled by the reverse relay contact and the reverse lever contact in series.

2. In combination, a railway switch, a relay, means for governing the relay by the switch, a lever for controlling the switch, means for controlling the lever by the relay, a signal for governing traffic over the switch, and means for controlling the signal by the relay and the lever.

3. In combination, a railway switch having a normal and a reverse position, a switch lever having a normal and a reverse position, means interposed between said lever and said switch for controlling said switch by said lever, a relay controlled by said switch to assume a normal or a reverse position responsive to the position of said switch, and signaling means controlled by said relay.

4. In combination, a railway switch having a normal and a reverse position, a switch lever having a normal and a reverse position, means interposed between said lever and said switch for controlling said switch by said lever, a relay controlled by said switch to assume a normal or a reverse position responsive to the position of said switch, and signaling means controlled by said relay and said switch lever.

5. In combination, a railway switch having a normal and a reverse position, a switch lever having a normal and a reverse position, means interposed between said lever and said switch for controlling said switch by said lever, a relay controlled by said switch to assume a normal or a reverse position responsive to the position of said switch, indication means controlled by said relay for preventing movement of said lever into said normal or reverse position until after said switch has moved into said normal or reverse position, a signal controlled by said relay for governing traffic over said switch, and means controlled by the lever for preventing said signal from being cleared unless said lever and switch are in corresponding positions.

6. In combination, a railway switch, a lever for the control thereof, a signal for governing traffic over the switch, a locking device for restricting the movement of said

lever, a relay responsive to said switch and energized by current of one polarity in one extreme position of the switch and by current of opposite polarity in the other extreme position of the switch, means for controlling said signal and said locking device by said relay, and means controlled by the lever for preventing said signal from being cleared unless said lever and switch are in corresponding positions.

7. In combination, a railway switch having a normal and a reverse position, a lever for controlling said switch and having a normal and a reverse position corresponding to the said positions of the switch, a relay controlled by said switch and energized in normal or reverse direction according as the switch is in normal or reverse position, lever locking means controlled by said relay for preventing complete movement of the lever to normal or reverse position until the switch has completed its movement to the corresponding position in response to a partial movement of the lever, and a signal governing traffic over said switch and controlled by said relay and by said switch controlling lever.

8. In combination, a railway switch, a lever for the control thereof, a relay controlled by said switch, an indication device controlled by said relay for controlling said lever, a signal for governing traffic over said switch, and means for governing said signal by said lever and said relay so that a proceed indication of said signal can be displayed only when said lever and said switch are in corresponding positions.

9. In combination, a railway switch having a normal and a reverse position, a lever also having a normal and a reverse position for controlling said switch, a relay responsive to said positions of the switch, an indication device controlled by said relay for governing said lever, a signal for governing traffic over said switch, and means controlled by said relay and said lever for checking coincidence in the positions of said lever and said switch before a proceed indication of said signal can be produced and maintained.

10. In combination, a railway switch having a normal and a reverse position, a relay controlled by said switch and having a normal and a reverse contact the former or the latter of which is closed according as the switch is in normal or reverse position, a lever for controlling said switch and having a normal and a reverse position corresponding to the said positions of the switch, two normal and two reverse contacts operated by said lever the former being closed when the lever is in normal position and the latter being closed when the lever is in reverse position, a pair of signals governing traffic over said switch in one direction and a pair of

signals governing traffic over said switch in the other direction, a circuit for one signal of one pair controlled by the normal relay contact and one normal lever contact, a circuit for one signal of the other pair controlled by the normal relay contact and by the remaining normal lever contact, a circuit for the remaining signal of the first pair controlled by the reverse relay contact and by one reverse lever contact, and a circuit for the remaining signal of the second pair controlled by the reverse relay contact and by the remaining reverse lever contact.

11. In combination, two routes for railway traffic, means for completing one or the other of said routes, a lever, means interposed between said lever and said first-mentioned means for controlling said first-mentioned means by said lever, an electromagnetic translating device responsive to reversals of current, means for controlling said translating device by said first-mentioned means, means for controlling said lever by said translating device, a circuit controlling lever, signaling means for each route for governing traffic over each route in both directions, means for controlling the signaling means for each route by said first mentioned lever and by said electromagnetic controlling device, and means for further controlling the signaling means for each route by said circuit controlling lever whereby traffic over either route is permitted to proceed in but one direction at a time.

12. In combination, two routes for railway traffic, a switch for completing one or the other of said routes according as said switch is in its normal or its reversed position, signals for each route one for each direction of traffic over said route, a controlling lever having a normal and a reverse position, means interposed between said lever and said switch for causing said switch to correspond in position with said controlling lever, a relay having a normal and a reverse position, means for causing said relay to correspond in position with said switch, means controlled by said relay for preventing said controlling lever from assuming said normal or reverse position until after said switch has been moved to its corresponding position, circuits for controlling said signals, means controlled by said circuit controlling lever and said relay for closing partially the circuits of the signals governing traffic over the route completed by said switch, and a signal controlling lever for completing the circuit of only one of the signals governing the last mentioned route.

13. In combination, a railway traffic controlling device, a lever, means interposed between said lever and said device for controlling said device by said lever, an electromagnetic translating device responsive to reversals of current, means for controlling said

translating device by said railway traffic controlling device, means for controlling said lever by said translating device, signaling means for governing traffic over said traffic controlling device, and means for controlling said signaling means by said lever and said electromagnetic translating device.

14. In combination, a railway traffic controlling device, a lever, means interposed between said lever and said device for controlling said device by said lever, an electromagnetic translating device responsive to reversals of current, means for controlling said translating device by said railway traffic controlling device, means for controlling

said lever by said translating device, a circuit controlling lever, signals for governing traffic over said traffic controlling device, circuits for said signals, and means for controlling said signal circuits by said circuit 20 controlling lever in conjunction with said first mentioned lever and said electromagnetic translating device.

In testimony whereof I affix my signature in presence of two witnesses.

HERBERT A. WALLACE.
